SPRAY GUN AIR VALVE

Robert Bertram Mitchell, Sanderstead, England, assignor to The De Vilbiss Company, Toledo, Ohio, a corporation of Ohio

Application January 25, 1951, Serial No. 207,724

1 Claim. (Cl. 251—229)

This invention relates to spray guns utilizing compressed air for atomizing the spray material and having diametrically opposed air jets for flattening the atomized material stream into fan shape. In order to secure spray patterns of various widths adaptable for effectively coating surfaces of different areas, it is customary to have an adjustable valve in the passage delivering air for such jets. The flattening force of the air jets is reduced or increased by closing or opening movement of the valve.

As usually constructed this valve has a tapered inner end which seats within the air passage, a threaded shank by which it is rotatably mounted, and an exterior knurled head for manual adjustment. In order to provide a broad range of adjustment a relatively fine thread is utilized. It is thus possible to set the valve for a very particular flow of air that will shape the spray pattern most suitably for a certain type of surface.

In many spray finishing operations the character of the products being coated is such that a single width of spray is satisfactory for all purposes. However, in other finishing processes, there are occasional surfaces of restricted area, for which a wide spray pattern, selected for a major part of the coating work, is not suitable.

Since excessive waste from overspray or too heavy a coating results from the use of too wide a spray pattern, under such circumstances it is desirable for the operator to temporarily screw the spray width valve at least part way toward a closed position. He must subsequently carefully open it again to the predetermined setting considered best for the predominant type of surfaces. Because of the fine thread on the valve shank, considerable rotary movement is required in this closing and opening of the valve and valuable time is lost in the accompanying interruption of the spraying operation.

The purpose of my invention is the provision of a valve structure for controlling the air delivered to flattening jets in a spray gun in which the advantage of close adjustment is retained and which in addition has means for easy and rapid closing and opening movement of the valve with stop means limiting the opening movement to the valve position previously selected for normal use.

This improved action is secured by mounting the valve for both gradual threaded adjustment and independent sliding axial movement. This is accomplished by having an unthreaded valve shank fitting snugly for relative axial movement within an exteriorly threaded rotatable sleeve and providing between the valve shank and sleeve a longitudinal slot and pin connection.

An embodiment of my invention is hereafter described in detail and illustrated in the accompanying drawings in which—

Figure 1 is a central vertical longitudinal section of a spray gun incorporating the invention;

Figure 2 is a similar section of the valve assembly of the spray gun of Figure 1; in this view the valve is in closed position;

Figure 3 is a side elevation partly in section of the valve assembly with the valve in open position; and

2

Figure 4 is a side elevation of the valve and the exteriorly threaded sleeve.

The spray gun of Figure 1 is a conventional design to which my invention has been adapted. It has a depending handle 1 in which there is an air supply passage 2. The air travels therethrough past valve 3, which is opened by rearward movement of the trigger 4 against the exteriorly extending valve spindle 5. The air flow continues upwardly through port 6 into the horizontal bore 7. The air is here divided into two parts, one travelling forwardly exteriorly of the hollow rod 8. This air passes through opening 9 into annular chamber 10, forwardly around the spray material tip and out the annular port surrounding the outlet end of the tip. This portion of the air atomizes the spray material discharged from the tip.

The second part of the air reaching bore 7 normally enters the lateral ports 12 into the interior of hollow rod 8. Under control of valve 13 this air travels forwardly out the open end of rod 8 into annular chamber 14 from whence it passes ahead to the outlets in horns 15. This air projected against opposite sides of the atomized material stream flattens it into fan shape.

The hollow rod 8, in addition to providing a passage 25 for the air going to the horns, serves to retain the spray head 16 in assembled relation with the spray gun body 17. It does this by having a forwardly facing shoulder abutting against the edge of the rearward opening of bore 7 and a threaded forward end engaging the sprayhead. 30 This double function of rod 8 is a feature of the particular spray gun utilized to illustrate an embodiment of this invention and is incidental to the invention. The latter may be as easily applied to spray guns not having this feature.

The interior of the rod 8 is divided into two parts by 35 the annular flange 18 forming a valve seat 19 for the valve 13. A sleeve 20 is threaded into the rear end of the rod 8, the joint between them being sealed by packing 21 held in place by nut 22. To resist accidental turning of the 40 sleeve 20 its forward end is slotted at 23 and the sections between the slots are sprung outwardly against the inner wall of rod 8. The valve 13 extends neatly through sleeve 20 and the exterior joint therebetween is sealed by packing 24 held in place by nut 25. For manual 45 adjustment of valve 13 there is mounted on the exterior end of the valve shank a knurled knob 26.

Midway of the sleeve 20 a longitudinal slot 27 is cut therethrough. Into this slot snugly fits the head of a screw 28 from the side of the valve shank. Through this 50 slot and screw engagement the valve may be moved longitudinally in relation to the sleeve within the limits of the length of the slot. With rotary movement the valve and sleeve must turn together.

In normal usage the valve 13 is in open position rearwardly spaced from the valve seat 19 with the head of the screw 28 against the rear end of slot 27. Should some adjustment in the position of the valve be desired the knurled knob 26 is turned. Through the engagement of the screw 28 on the valve shank with the slot 27 in the sleeve 20, the latter is rotated by the turning of the knob 26 and is gradually moved axially through its threaded engagement with the interior of rod 8. The degree of opening of the valve is thus modified according to requirements.

65 Should a succession of comparatively large surface areas to be coated be interrupted by narrow surfaces too restricted in area to be properly coated by a fan pattern the knob 26 is pushed forwardly sliding the valve to its seat with the head of screw 28 travelling lengthwise of the slot 27.

When the work for the narrow spray pattern is completed the knob 26 is pulled rearwardly until the head of

the screw 28 reaches the rear end of the slot 27. As this doesn't disturb the rotary position of the sleeve, the fan pattern previously selected for the regular run of surfaces is thus again produced.

The length of the threads between the sleeve 20 and the interior of rod 8 is such that the valve may be firmly held to its seat for a long spell of coating of surfaces of limited dimensions by turning the valve and coating sleeve until the valve reaches its seat.

From the preceding it may be understood that the slot and screw engagement between the valve shank and sleeve in association with the threaded mounting of the sleeve provides means for both gradual adjustment of the valve position and rapid closing and reopening sliding movement of the valve.

While a slot and screw engagement between the valve shank and the surrounding sleeve is utilized in the preferred embodiment, it is realized that there are analogous structures which would serve as well. For instance a groove of sufficient depth would function as effectively as the slot. Then too, a pin or flattened tongue could be feasibly substituted for the screw. It is not considered that such replacements would depart from the spirit of the invention and that "slot and screw" as herein specified should accordingly be interpreted broadly.

Also, it may be well to point out that it is not essential that the slot be in the sleeve and the pin or screw be in the valve shank as the reverse positioning would work as well. In addition, it may be observed that the valve shank could have a threaded engagement with the sleeve and the latter a slot and screw engagement with the rod without any loss in functions over the preferred form. For this reason the scope of this invention is not considered limited to a particular location of such engaging structures.

Having thus described my invention, what I claim as new and desire to secure by Letters Patent is:

In a spray gun air valve, a unitary valve casing with

an air passage therethrough, said passage having a lateral entering port and an axial discharge port, a valve seat within the passage between the two ports, a valve for axial adjustment toward and away from said seat, a valve shank, a rotatable sleeve threadedly engaged within the casing and encompassing said shank, a pin and longitudinal slot connection between the sleeve and shank within the valve casing, the pin of said connection extending radially from the valve shank and the longitudinal slot of said connection located in the wall of the sleeve and cutting through the portion of the sleeve which is externally threaded for engagement within the casing, a single manipulable head on the outer end of said shank by a manual push or pull of which the valve is moved axially within the limits permitted by the pin and slot connection toward or away from the valve seat, and by a manual turning of which the sleeve is rotated upon its threaded engagement within the casing through the pin and slot connection between the sleeve and the shank, means located intermediate the manipulable head and the pin and slot connection for frictionally retaining the valve in any selected position relative to the sleeve, and means for frictionally retaining the sleeve in any selected position relative to the casing.
